UNITED STATES PATENT OFFICE

155,171

DESIGN FOR A COMBINED BABY SEAT
AND PLAY PEN

Gertrude Levy, Brooklyn, N. Y.

Application June 27, 1947, Serial No. 139,966

Term of patent 3½ years

(Cl. D34—15)

To all whom it may concern:

Be it known that I, Gertrude Levy, a citizen of the United States, residing in Brooklyn, county of Kings, and State of New York, have invented a new, original, and ornamental Design for a Combined Baby Seat and Play Pen, of which the following is a specification, reference being had to the accompanying drawing, forming part thereof.

In the drawing:

I claim:

The ornamental design for a combined baby seat and play pen, as shown.

GERTRUDE LEVY.
